[57] CLAIM

The ornamental design for glider chair with side table, as shown and described.

DESCRIPTION

FIG. 1 is a front perspective view of the glider chair with side table showing our new design;

FIG. 2 is a side elevational view taken from the right-hand side of FIG. 1;

FIG. 3 is a side elevational view taken from the left-hand side of FIG. 1;

FIG. 4 is a front elevational view;

FIG. 5 is a rear elevational view;

FIG. 6 is a top plan view;

FIG. 7 is a bottom plan view thereof;

FIG. 8 is a front perspective view of a glider chair with side table showing a modification of our new design;

FIG. 9 is a side elevational view taken from the right-hand side of FIG. 8;

FIG. 10 is a side elevational view taken from the left-hand side of FIG. 8;

FIG. 11 is a front elevational view of FIG. 8;

FIG. 12 is a rear elevational view of FIG. 8;

FIG. 13 is a top plan view of FIG. 8;

FIG. 14 is a bottom plan view of FIG. 8;

FIG. 15 is a front perspective view of a glider chair with side table showing another modification of our new design;

FIG. 16 is a front elevational view of FIG. 15;

FIG. 17 is a rear elevational view of FIG. 15;

FIG. 18 is a top plan view of FIG. 15; and,

FIG. 19 is a bottom plan view of FIG. 15.

The broken line showing of environmental structure is for illustrative purposes only and forms no part of the claimed design.
